UNITED STATES PATENT OFFICE.

JOHN E. W. FOGAL, OF QUINCY, ILLINOIS.

ELEVATOR-GATE-OPERATING DEVICE.

1,411,996.

Specification of Letters Patent. Patented Apr. 4, 1922.

Application filed July 16, 1920. Serial No. 396,670.

To all whom it may concern:

Be it known that I, JOHN E. W. FOGAL, a citizen of the United States, and a resident of Quincy, in the county of Adams and State of Illinois, have invented a new and useful Improvement in Elevator - Gate-Operating Devices, of which the following is a full, clear, and exact description.

My invention relates to improvements in elevator gate operating devices, and it consists in the combinations, constructions and arrangements herein described and claimed.

An object of the invention is to provide a device, by means of which a gate on the end of an elevator car may be raised at will, and which, when raised, will also raise a hatch gate associated therewith.

A further object of the invention is to provide an electric elevator provided with gate raising means for electrically operated elevators which will cut off the current to the elevator when the gates are open, thereby preventing the operation of the elevator until the gates have been restored to their normally closed position.

A further object of the invention is to provide an electrically operated elevator which may be moved upwardly and downwardly, with an electrical gate operating means, which may be brought into action at will to cause the opening of the elevator gate and also the hatch gate.

A further object of the invention is to provide gate operating means for causing the raising of the elevator gate, including an emergency device, which prevents the dropping of the gate should the cable which raises the gate break.

A further object of the invention is to provide an engaging mechanism on the elevator gate which is arranged to engage the hatch gate for raising the latter, with means for normally locking the engaging means out of operative position.

Other objects and advantages will appear in the following specification, and the novel features of the invention will be particularly pointed out in the appended claims.

My invention is illustrated in the accom-

panying drawings, forming part of this application, in which—

Figure 1 is a view showing an electrically operated means for raising the elevator gate independently of the upward and downward movement of the elevator,

Figure 2 is a face view of an elevator gate,

Figure 3 is an end view of the gate shown in Figure 2,

Figure 4 is a face view of a hatch gate,

Figure 5 is an end view of the hatch gate shown in Figure 4,

Figure 6 is a detail view showing portions of the elevator gate operating mechanism,

Figure 7 is a detail view showing the relation of the elevator gate operating mechanism with the hatch gate, and

Figure 8 is a detail view showing a portion of the hatch gate and a plate carried thereby.

The invention is designed to be applied to gates of the type set forth in the patent to John E. W. Fogal, Serial No. 1225606 of May 8, 1917; that is to say, to electrically operated gates which are raised or lowered independently of the upward or downward movement of the elevator. Figure 1 shows a gate of this type, this figure being primarily for the purpose of setting forth the type of gate operating means to which the invention is applied, since it will be understood that other arrangements for raising or lowering the gate, independently of the upward or downward movement of the elevator, might be used, without departing from the spirit of the invention.

Referring to Figure 1, 1 denotes the elevator in general. This may be raised or lowered by any suitable means (not shown). In connection with the elevator I make use of an auxiliary device which is fastened to the side wall of the hatch 2 under the pent house 3. As will be seen from the drawings, it consists of heads 4 and 5 secured to the wall and bearing guide rods 6, along which a sheave casing 7, an upper sheave 8, and a lower sheave 9 are arranged to travel. A cable 10 is secured at 11 to the wall of the hatch, passes downwardly around the sheave 100

8 and upwardly around the drum 12 in the pent house, which is driven by an electric motor 13. A second cable 14 is secured to the platform of the elevator 1, passes around 5 a fixed sheave 15 at the bottom of the elevator shaft, thence upwardly around the sheave 9, downwardly under a fixed sheave 16 attached to the elevator, upwardly over the pulleys 17 and 18, and thence downwardly, 10 being fastened to the elevator gate 19.

It will be seen by this arrangement that when the elevator moves upwardly or downwardly, the cable 14 will pass over the sheaves and pulleys 9, 16, 17 and 18 without 15 effecting the elevator gate 19, because the cable is attached at both ends to parts of the elevator. If, however, the drum 12 is operated to wind up the cable 10, then the sheave casing 7 will be raised, thus pulling on the 20 cable 14 and raising the gate. A reversal of the winding drum 12 will close the gate.

Referring now particularly to Figures 2 and 3, I have shown a gate which consists of a frame 19 having bars 20 which may be 25 filled in with spindles, slats, or hardware cloth, if desired. The upper part of the frame bears a casting 21, in which are mounted rollers 22. The cable 14 is secured to a plate 23, to which are secured short 30 lengths of cable 24 which pass around the rollers 22, and are connected to the ends of rods 25, which are disposed in guides 26, and whose ends may extend into notches 27 in vertically disposed guide members 28 at 35 each end of the gate. Each rod is provided with a spring 29 which engages a collar 30 on the rod at one end and one of the guides 26 at the other. When the drum 12 is operated to raise the gate, the upward movement 40 of the cable 14 it will draw the rods 25 out from the notches against the tension of the springs 29, so that the gate is free to move upwardly or downwardly as long as the weight of the gate is on the cable 14. If the cable 45 should break, the rods 25, under the influence of the springs 29, will be forced outwardly into the notches 27, thereby preventing the gate from falling. Also, when the gate has 50 reached its lower limit, so that the weight of the gate is taken off from the cable 14, the springs will cause the rods 25 to enter the notches, thereby locking the gate in position.

Referring to Figure 6, it will be seen that 55 I have provided a plate 31, to which is pivotally connected a locking bar 32 which is normally pressed on by a spring 33. A pawl 34 is carried by a bracket 35 which is slotted to permit a free movement of the pawl. The 60 latter is pivotally mounted at 36 in the bracket for oscillatory movement about its pivot. A spindle 37 is slidably mounted in the bracket 38, passes through the bracket 35 and bears a roller 38^a which runs in the

guide groove 39 of the vertical guide member 28. The pawl 34 is of the shape best shown in dotted lines in Figure 7. It has a hook 40 on one end, and at the other end is provided with a roller 41 which is arranged to normally engage a switch arm 42 carried by 70 a bracket 43 secured to the gate guide 28. The locking bar 32 is bent laterally at 32^a, and is arranged to rest on a bracket 44 secured to the gate guide 28. A U-shaped plate 45 is bolted to the gate and serves as a guide plate 75 for the locking plate 32 to prevent the latter from swinging outwardly.

As will be seen from Figures 7 and 8, a hatch gate 46 is provided with a plate 47 having a rounded lower edge 48, and also a bearing or retaining portion 49 for a pin or shaft 50, which bears at its outer end a roller 51 arranged to run in the guideways 52. The plate 47, as will be seen from Figures 4 and 7, is secured to the hatch gate so 80 as to be engaged by the pawl 34 when the latter is swung outwardly, as when the elevator gate is being raised. It will be understood that a pawl 34 is disposed at each end of the elevator gate, and that the plate 47 85 is disposed at each end of the hatch gate, each end of the gate being equipped with the engaging apparatus described above.

From the foregoing description of the various parts of the device, the operation thereof may be readily understood. Assume that the elevator gate is closed. The elevator may be raised or lowered without operating the gate by the apparatus, such as that set forth in Figure 1. Now if it is desired to 100 raise the elevator gate, the motor 13 is energized by closing the energizing circuit (not shown). This will cause the elevator gate to be raised in the manner described. At the first upward movement of the elevator 105 gate, the roller 41, which normally rests on the switch arm 42, is lifted, and the switch arm thereby is permitted to raise under the action of the spring (not shown), so that the circuit of the motor which raises 110 and lowers the elevator is broken. As stated above, the latter may be of any suitable type. When the gate has been raised sufficiently, the pawl 34, which is overbalanced, swings forwardly, and the end of the locking plate 115 32 drops down behind the shoulder 54 on the pawl 34, thereby holding the pawl in its outer position. Now as the elevator gate rises, the hook 40 will engage behind the plate 47, and will carry a hatch gate up 120 with it. It is impossible to start the elevator while the gates are raised, because of the fact that the current has been cut off at the switch 42. On the reversal of the motor 13, the gate will be lowered. When the 125 end 32^a of the locking plate 32 reaches the bracket 44 (see Figure 7), any further movement of the elevator gate will cause the lock-

ing plate to lift away from the shoulder 54, thus releasing the pawl, while the contact of the roller 41 with the switch 42 will close the switch, and at the same time will cause 5 the pawl to be retracted into the position shown in dotted lines in Figure 7, which is the normal position of the pawl when the gate is closed. The elevator, of course, can be started, since the switch is now closed.

10 I claim:

1. The combination of an elevator, an elevator gate carried thereby, power means for raising and lowering said elevator gate independently of the movement of the elevator, a hatch gate, an overbalanced pawl carried by said elevator gate, means for keeping the pawl retracted when the elevator gate is closed, a switch arranged to be closed by the pawl when the latter is in its retracted position, said pawl swinging outwardly when the elevator gate is raised, and means carried by the hatch gate and arranged to be engaged by the pawl for raising the hatch gate.

25 2. The combination of an elevator, an elevator gate carried thereby, power means for raising and lowering said elevator gate independently of the movement of the elevator, a hatch gate, an overbalanced pawl carried by said elevator gate, means for keeping the pawl retracted when the elevator gate is closed, said pawl swinging outwardly when the elevator gate is raised, and means carried by the hatch gate and arranged to be 35 engaged by the pawl for raising the hatch gate.

3. The combination with an elevator of a vertically movable elevator gate, a hatch gate, an overbalanced pawl carried by said 40 elevator gate, means for holding the pawl

normally in a retracted position when the elevator gate is in its lowered position, said pawl swinging outwardly when the elevator gate is raised, locking means for locking the pawl in its outer position when the gate is 45 raised, and means carried by the hatch gate and arranged to be engaged by the pawl for raising the hatch gate.

4. The combination with an elevator of a vertically movable elevator gate, a hatch 50 gate, an overbalanced pawl carried by said elevator gate, means for holding the pawl normally in a retracted position when the elevator gate is in its lowered position, said pawl swinging outwardly when the elevator 55 gate is raised, locking means for locking the pawl in its outer position when the gate is raised, means carried by the hatch gate and arranged to be engaged by the pawl for raising the hatch gate, and means for moving the locking means to release the pawl when the elevator gate is lowered.

5. The combination with an elevator of a vertically movable elevator gate, a hatch 60 gate, an overbalanced pawl carried by said elevator gate, means for holding the pawl normally in a retracted position when the elevator gate is in its lowered position, said pawl swinging outwardly when the elevator 65 gate is raised, locking means for locking the pawl in its outer position when the gate is raised, means carried by the hatch gate and arranged to be engaged by the pawl for raising the hatch gate, means for moving the locking means to release the pawl when the elevator 70 gate is lowered, and a switch arranged to be engaged and released by the pawl when the elevator gate is in its lowered position.

JOHN E. W. FOGAL,
